COMBINATION CABANA AND SOLARIUM THEREFOR

Mike Tecton, 115 5th St. NE.,
Washington, D.C. 20002

Filed Sept. 3, 1965, Ser. No. 86,849

Term of patent 14 years

(Cl. D83—1)

FIG. 1 is a perspective view of a combination cabana and solarium therefor, embodying my new design;

FIG. 2 is a front end elevational view thereof;

FIG. 3 is a side elevational view thereof;

FIG. 4 is a side cross sectional view thereof taken along line 4—4 of FIG. 3;

FIG. 5 is a rear end view thereof.

I claim:

The ornamental design for a combination cabana and solarium therefor, substantially as shown.
